UNITED STATES PATENT OFFICE.

JOHN HENRY BARTELS, OF CHICAGO, ILLINOIS.

COUNTING AND EMBOSsing MACHINE.

Application filed January 18, 1924. Serial No. 636,979.

To all whom it may concern:

Be it known that I, JOHN HENRY BARTELS, a citizen of the United States, residing at Chicago, in the county of Cook and State 5 of Illinois, have invented certain new and useful Improvements in Counting and Embossing Machines, of which the following is a specification, reference being had to the accompanying drawings, and to the reference characters marked thereon, which form 10 a part of this specification.

This invention relates to numbering and embossing machines, and more particularly to such a machine adapted for use in polling 15 places for marking ballots.

It is the general practice for a judge of election or other designated election official to initial in lead pencil each ballot as it is handed to the voter, and to require the 20 voter to so fold his ballot while in the voting booth as to expose the initialed portion to view, thus identifying the ballot he is about to deposit in the ballot box. When the polls are closed, there is nothing to prevent 25 the dishonest election official, when the ballot box is opened for the purpose of counting the ballots, from substituting other initialed ballots, surreptitiously marked for his particular candidate, for ballots regularly voted.

The principal object of my invention is to provide a machine for marking the ballots with certain marks whereby the above stated and other election frauds are obviated.

To the attainment of this and other objects, I have provided a device having suitable dies whereby each ballot may be stamped or embossed with the ward and precinct number and any other desired permanent or 40 special data, and at the same time give the ballot a serial number. The difference between the highest number shown on the machine at the close of the day's voting, and the number indicated thereon at the beginning 45 of the day will, of course, indicate the number of ballots stamped, and correspond with the number of ballots actually voted. No substitution of another ballot for one thus stamped and voted could thereafter be 50 made without detection of the fraud because of the lack of official marks thereon, or if it did bear the proper stamping marks and had not been regularly voted, the number of ballots in box would not correspond with the

number indicated by the machine as having 55 been voted.

My invention consists in the novel device and combination of devices illustrated in the accompanying drawings and herein described and claimed. 60

In the drawings:

Fig. 1 is a perspective view of a machine embodying my invention.

Fig. 2 is a top plan view of the same, partly in section. 65

Fig. 3 is a rear elevation of the machine, partly in section, the section being in the plane of the dotted line 3—3 of Fig. 4.

Fig. 4 is a side elevation of the machine, partly in section, with the end plates removed to show the interior construction in elevation. 70

Fig. 5 is a vertical sectional view taken in the plane of the dotted line 5—5 of Fig. 4.

Fig. 6 is a vertical sectional view taken 75 in the plane of the dotted line 6—6 of Fig. 4.

Fig. 7 is a top plan view, partly in section, looking down from the plane indicated by the dotted line 7—7 of Fig. 4.

Fig. 8 is a fragmentary plan view of a 80 portion of the die.

Fig. 9 is a fragmentary front view showing the upper part of the platen with a ballot in position thereon and the lower part of the die which cooperates therewith. 85

Fig. 10 is a vertical sectional view of a portion of the machine, the section being taken on the dotted line 10—10 of Fig. 3.

Referring now to that form of my invention delineated in the said drawing, A represents the device as a whole, comprising a base B, a lower housing C, a movable head or housing D, an upright frame member or standard E, guide rods F, F, a rotatable operating shaft G and means H for operating the shaft,—in this instance, a hand wheel. 90

The lower housing C is provided at one end with an end plate 1 having a hasp 3 hingedly secured thereto and adapted to engage a staple 4 on the corresponding end plate 2 of the movable housing D whereby the machine may be locked by a padlock 5, if desired. The standard or frame member E extends upwardly from the base B and terminates in an enlarged head 6 covered by a removable cap 7. The head 6 is formed to provide a bearing or seat for an enlarged 100 105

part 8 of the shaft G. 9 is a ratchet wheel on shaft G which is engaged by the spring pressed pawl 10 whereby the shaft is prevented from being rotated excepting in one direction.

The guides F, F, extend upwardly in parallel, spaced apart relation, one on either side of the standard E, their upper portions passing through somewhat long bearings 11 on the rear of the housing or movable member D. Thus the housing D may be readily moved from its upper position to the housing C and back again, being carried in a perfectly straight path so that the male die 12 on its lower face will properly cooperate with the platen 13 or female portion of the die on the housing C.

The following described means are employed to actuate the housing D from the shaft G. On the forward face of the enlarged part 8 of said shaft is secured a round stud or shaft extension 14, the longitudinal axis of which stud is eccentrically located with respect to the central longitudinal axis 25 of the shaft. This stud 14 is mounted in a box bearing 15 which latter has sliding engagement with top and bottom parallel plates or ways 16, 16, on the top of and secured to the head or housing D, and permitting a lateral travel of the box bearing. It will be understood that when the shaft G is given one complete rotation, the head D will, therefore, be moved down and then up, the travel being determined by the 35 amount of eccentric relation of the stud and the shaft G. A protective housing 17 may be used to cover the parts just described.

Upon the lower face of the movable head D is a die 12 cut in this instance to indicate 40 6th ward, 9th precinct, Republican, to be embossed upon a primary election ballot, but of course the die may be cut to impress any desired word, picture or device. The upper face of the housing C is utilized as 45 the female part 13 and is so cut as to properly cooperate with the male portion 12 to emboss, stamp or imprint the desired mark, symbol or lettering upon the ballot 18 or other article.

50 In each of the housings C and D, I provide a desired number (in this instance 3) of die discs having their faces cut to be the female and the male dies, respectively, to indicate any data desired. In this instance 55 I have illustrated merely numerals and so arranged the discs and their respective parts that each complete cycle of operations shall be recorded, or rather, numbered.

In the housing C I mount a rotatable 60 shaft 19 extending from the front to the rear. Upon this shaft 19 is a disc 20 provided with a plurality of equally spaced apart teeth or pins 21. A movable pawl 22 is adapted to engage the pins of the disc 20 and rotate the disc and the shaft 19.

This pawl 22 is secured to the lower end of a plate 23 which is fastened to and moves with the head or housing D. The plate 23 is so positioned that it lies in a vertical plane just inside of the rear wall of the casing or housing D. A spring 24 fastened to said plate 23 exerts tension upon the pawl 22 and tends to press it against one of the pins 21. When the head D is moved downwardly from the position shown in Fig. 5, the pawl 22 will of course move with it and finally engage the next subjacent pin (indicated at 25 in Fig. 5), and when the head D is moved upwardly, carrying with it the plate 23 and pawl 22, the hooked end of said pawl 22 being then engaged underneath the pin 25, will pull said pin upwardly with the result that the disc 20 is rotated in the direction indicated by the arrow. A spring 25 pressed stop arm 26 secured at 27 to the rear wall of the lower housing C prevents the disc 20 from being rotated in the opposite direction to that in which it is being rotated when the end of the pawl 22 is descending, and its tip first engages the pin 25.

A similar shaft 28 is located in the head D in alignment with and parallel to the shaft 19. Said shaft 28 carries a disc 29 provided with pins 30 which are engaged by a pawl 31 pivoted at 32 to a plate 33. The plate 33 is secured to the lower housing C and extends upwardly therefrom into the upper head or housing D and adjacent to the rear wall thereof. Said plate 33 carries a tension spring 34 which bears against the pawl 31.

It will be readily understood from this construction that as the head D is moved down toward the housing C, the pin 29 seen in Fig. 5 to be in engagement with the pawl 31, will slip by and be disengaged from said pawl and the next pin above it, indicated at 35, will be brought down into a position where it in turn is engaged by the end of the pawl 31; and that in the return movement, when the head D is being raised into the position shown in Fig. 5, the engagement of the pin 35 with the pawl 31 will cause a rotation of the disc 29 and the shaft 28 in the direction indicated by the arrow. A fixed spring pressed stop 36 in the head D in engagement with the pins 30 on the side of the shaft 28 opposite to the pawl 31, of course, will prevent the disc 29 and the shaft 28 from being rotated in more than one direction.

Upon the shaft 19 are a series of discs 37, 38 and 39, and on the shaft 28 are a similar set of discs 40, 41 and 42. Each of these discs are provided with a plurality of surfaces carrying male and female dies for numerals, indicated at 43. These sets of discs, 37 to 42, inclusive, constitute a conventional type of numbering or counting device, being operatively connected by transmitting gears

- in the usual manner, so that the ballots or sheets 18, being successively placed upon the table C will be numbered serially and consecutively, each time the head D descends.
- 5 As the details of construction of this counting device constitute no part of the present invention, it is considered not necessary to describe the same, as the operation will be readily understood.
- 10 It will be understood from the foregoing description that with this stamping and numbering device in use, for example, at a polling place, the operation will be as follows:
- 15 The ballot 18 is placed upon the table C, the shaft G rotated one complete revolution, causing the head D to descend and impress upon the ballot the markings indicated in Fig. 8, and the numerals "001."
- 20 The bringing of the head D to its raised position turns one set of numbering discs, for example, the discs 37 and 40, one notch so as to bring in apposition those faces bearing the numerals "2." The first ballot will then be withdrawn, the second ballot inserted, the shaft G given one turn and the second ballot will then be embossed with the ward and precinct numbers, as indicated, and the numerals "002" etc.
- 25 Thus at the end of any given period, or when the polls close, the total number of ballots thus marked will be registered by the total count on the discs 39, 38 and 37.
- 30 Although this machine has been designed more particularly for use at voting places, it will be readily understood that it may be used for a variety of other purposes.
- I claim as my invention:
1. In a machine of the class described, a frame, a pair of vertically disposed, separated guide rods on said frame, a rotatable operating shaft journalled in the upper part of said frame, an upper housing movably mounted upon said guide rods, a plurality of elements constituting a complete counting unit rotatably mounted in each housing, adapted for cooperative action to emboss a sheet or ballot inserted therebetween, a rotatable disc provided with pins operatively connected to operate the counting unit in each head, a member fixedly mounted on the lower housing and projecting into the upper housing, a spring pressed pawl pivotally mounted on said member to operatively engage the pins on the rotatable disc of the movable housing, a second member fixedly mounted on the movable housing and projecting into the fixed housing, a spring pressed, hooked pawl pivotally mounted on said second member to operatively engage the pins on the rotatable disc of the fixed housing, and means for giving the movable housing a reciprocation upon the rotation of the operating shaft.
2. In a machine of the class described, a frame, a pair of vertically disposed, separated guide rods on said frame, a rotatable operating shaft journalled in the upper part of said frame, an upper housing movably

4 mounted upon said guide rods, a plurality of elements constituting a complete counting unit rotatably mounted in each housing, adapted for cooperative action to emboss a sheet or ballot inserted therebetween, a rotatable disc provided with pins operatively connected to operate the counting unit in each head, a member fixedly mounted on the lower housing and projecting into the upper housing, a spring pressed pawl pivotally mounted on said member to operatively engage the pins on the rotatable disc of the movable housing, a second member fixedly mounted on the movable housing and projecting into the fixed housing, a spring pressed, hooked pawl pivotally mounted on said second member to operatively engage the pins on the rotatable disc of the fixed housing, and horizontally disposed guide-ways on the movable housing, a bearing box slidably mounted therebetween, a stud eccentrically extending from the operating shaft and rotatably mounted in said bearing box, the adjacent faces of the movable and fixed housings being provided with aligned openings through which the operating faces of the respective counting units act in co-operation for marking the ballot when placed upon the face of the lower housing.

5 5. In a machine of the class described, a frame, a pair of vertically disposed, separated guide rods on said frame, a rotatable operating shaft journalled in the upper part of said frame, an upper housing movably mounted upon said guide rods, a plurality of elements constituting a complete counting

40 unit rotatably mounted in each housing, adapted for cooperative action to emboss a sheet or ballot inserted therebetween, a rotatable disc provided with pins operatively connected to operate the counting unit in each head, a member fixedly mounted on the lower housing and projecting into the upper housing, a spring pressed pawl pivotally mounted on said member to operatively engage the pins on the rotatable disc of the movable housing, a second member fixedly mounted on the movable housing and projecting into the fixed housing, a spring 45 pressed, hooked pawl pivotally mounted on said second member to operatively engage the pins on the rotatable disc of the fixed housing, and means for giving the movable housing a reciprocation upon the rotation of the operating shaft, the adjacent faces of the movable and fixed housings being provided with aligned openings through which the operating faces of the respective counting units act in cooperation for marking the ballot when placed upon the face of the lower housing, said faces of the movable and fixed housings being also provided with cooperating companion dies for stamping predetermined characters on each ballot.

50 55 In testimony that I claim the foregoing as my invention I affix my signature, in the presence of two witnesses, this 16th day of January, 1924.

60 JOHN HENRY BARTELS.

Witnesses:

TAYLOR E. BROWN,
B. L. MACGREGOR.
